COMBINED FLOOR CLOCK AND CURIO CABINET

Leonard Eisen, 14 Lomas Lane,
Montvale, N.J. 07645

Filed Oct. 19, 1973, Ser. No. 407,785

Term of patent 14 years

Int. Cl. D10—01

U.S. Cl. D10—16

FIG. 1.

FIG. 2.

FIG. 1 is a left front perspective view of a combined floor clock and curio cabinet showing my new design; and

FIG. 2 is a right side elevational view thereof, the rear being flat, plain, and unornamented.

I claim:

The ornamental design for a combined floor clock and curio cabinet, as shown and described.
